E. J. McCARTY,

TUBE BLOWER.

APPLICATION FILED OCT. 9, 1911.

1,155,750.

Patented Oct. 5, 1915.

UNITED STATES PATENT OFFICE.

EUGENE J. McCARTY, OF CLINTON, MASSACHUSETTS, ASSIGNOR TO THOMAS J. McNAMARA, OF CLINTON, MASSACHUSETTS.

TUBE-BLOWER.

1,155,750.

Specification of Letters Patent.

Patented Oct. 5, 1915.

Application filed October 9, 1911. Serial No. 653,573.

To all whom it may concern:

Be it known that I, EUGENE J. McCARTY, a citizen of the United States, residing at Clinton, in the county of Worcester and 5 State of Massachusetts, have invented a new and useful Tube-Blower, of which the following is a specification.

The principal objects of this invention are to provide a simple, strong, and convenient 10 tube blower which can be connected with a flexible steam hose and can be moved around easily by the operator, or conveniently suspended from above; and which is adapted to be supported at the end by the tube to be 15 cleaned; also to provide said tube blower with means whereby the steam discharged therefrom into the tubes will impinge on the surface of the tubes in an angular direction equally all around so as to loosen the scale 20 and the like therefrom. This latter object is secured by directing the steam against the tubes in a hollow conical spray. The invention also involves improvements in details of construction as will appear hereinafter.

Reference is to be had to the accompanying drawings, in which—

Figure 1 is a side view of a tube blower constructed in accordance with this invention with parts broken away and shown in 30 central longitudinal sectional view; and Fig. 2 is an end view of the same.

The invention is shown in a form in which the parts are operated by a long handle 10 which can be conveniently manipulated by 35 the operator. This handle fits into the leg 11 of a fitting 12, said fitting being provided with another leg 13 opposite the leg 11, but at an angle thereto, and with a leg 14 at right angles to the leg 13. The legs 13 and 40 14 have communicating passages and the leg 14 is designed for the reception of a flexible hose for supplying steam, compressed air, or the like to the interior of the fitting. The leg 11 is solid so as to provide 45 a rigid hold for the handle.

In the end of the leg 13 is fitted a long pipe 15, on the other end of which is the hub 50 of a nozzle 16. This nozzle has a chamber 17 for receiving the steam or compressed air from the pipe 15, and is provided with a bridge 18 for receiving a bolt or screw 19. This bolt or screw holds a convex preferably 55 hemispherical baffle plate 20 the position of which is adjusted by putting in one or more washers 21 between the baffle plate and the

bridge. The nozzle is also provided with an interior conical surface 22 at its end, furnishing a circumferential continuous conical body or base ring open at the end. The baffle plate is adjusted to proper position with respect to this surface so that the steam issuing from the nozzle will be forced 60 to assume the form of a hollow cone. In this way the steam will impinge on the inner surface of the tubes all around the same at an angle so as most efficiently to disengage the scale and the like from such surfaces.

The nozzle is ribbed equally around on its outer surface. It will be seen that these ribs or projections 23 taper from the outlet end of the nozzle, allowing the nozzle to enter the tube easily, and they extend in a convex shape outward from the body of the nozzle keeping the same in the center of the tube, 70 tending to form a vacuum and drawing air into the tube from back of nozzle, increasing the velocity and power of steam and compressed air for cleaning. In actual use the vacuum is so strong that if a handkerchief 75 or glove is held within a few inches of the tube it will be snatched from the hand and drawn into the tube, and if it does not entwine on the head or nozzle it will be blown out the other end almost instantly. The ribs 80 also prevent the clogging of this opening and prevent the nozzle coming so far to one side of the tube as to be inefficient for cleaning the opposite side.

On the leg 11 of the fitting 12 is shown an 85 eye 24 by which the whole device can be suspended. The handle 10 preferably is of such length that it substantially counter balances the rest of the blower when hung from this eye so that the weight of the device can be 90 supported from above by a flexible connection and yet the implement may be manipulated readily by the handle. This is an important advantage in the use of the device.

In addition to the advantages which have 95 been mentioned it will be seen that the device not only is very easy to use and simple to manipulate, but that it consists of very few parts and those of a very simple character, that it contains no moving parts and no elements likely to get out of order, and that it is designed so as to be of maximum utility for this purpose.

Although I have illustrated and described a preferred embodiment of the invention I 110

am aware that many modifications can be made therein by any person skilled in the art without departing from the scope of the invention as expressed in the claim. Therefore, I do not wish to be limited to all the details of construction herein shown and described, but

What I do claim is:—

10 A nozzle for cleaning out boiler tubes having a cylindrical hub and a conical base ring at the end of the hub and provided with a concave baffle plate located within said base ring and spaced therefrom, a perforated bridge across the nozzle at the end of the 15 conical base ring thereof, a bolt mounted on

the bridge for holding said baffle plate in position, spacing devices between the bridge and baffle plate for regulating and adjusting the position of the baffle plate relative to the inner surface of the conical base ring, 20 and external convex radial projections extending longitudinally the whole length of the hub and base ring and spaced apart.

In testimony whereof I have hereunto set my hand, in the presence of two subscribing 25 witnesses.

EUGENE J. McCARTY.
